SULPHONATION PROCESS

Charles H. Lighthipe, Bloomfield, N. J., assignor to
National Oil Products Company, Harrison,
N. J., a corporation of New Jersey

No Drawing. Application December 23, 1941,
Serial No. 424,142

11 Claims. (Cl. 260—400)

This invention relates to a novel process for preparing sulphonated oils, fats and waxes and in particular to a process for producing such materials of high SO₃ having a substantial free fatty acid content.

For certain purposes it is desirable to use sulphonated oils, fats or waxes having a high content of free fatty acids, as well as a high SO₃ content, notably in certain textile, leather and paper treating or manufacturing processes where the oils must be used in acid media without loss of wetting power.

Sulphonated oils are generally prepared by a process which involves (1) the step of "sulphonating" wherein the raw oil or like fatty material is reacted with sulphuric acid to form a sulphonation mass; (2) the step of "washing" wherein the sulphonation mass is dropped into a quantity of wash water wherein most of the unsupent acid is washed out of the mass; and (3) the step of "panning" wherein the washed oil is permitted to stand for the purpose of allowing excess water to separate out, i. e. until most of the water entrained therein separates out. The unsupent acid remaining in the oil after the washing step and also the acid sulphate radicles combined with the oil are generally neutralized before or at the commencement of the panning step. Customarily, in order to develop large quantities of free fatty acids in sulphonated oils produced as above set forth, the oil is left for some time in contact with the acid water in the "washing" step, or the water in the "panning" step is allowed to become acid, the acid in each case acting as a catalyst to hydrolyze the oil and to produce the desired amount of fatty acids. However, during this process of hydrolysis, not only is the oil hydrolyzed to form free fatty acids and degraded glycerides, but also a certain amount of the combined SO₃ is split off from the oil. This splitting is undesirable in several respects: first, in that it necessitates prolonged sulphonation of the oils in order to attain any given degree of sulphonation in the final product; second, in that it is impossible to produce a sulphonated oil having both a high acid value and a high SO₃ content—for instance, heretofore when sulphonated castor oil has been produced with an acid value in excess of 100, it has been impossible to obtain an SO₃ content in excess of 5% or 6%; and finally, in that the splitting off of the combined SO₃ results in hydroxylation of the oil, which tends to make the oil cloudy, and in many cases, solid at ordinary temperatures.

Accordingly, it is an object of this invention to produce sulphonated oils of high free fatty acid content without subjecting the oils to prolonged contact with acid liquors with consequent sacrifice in SO₃ content.

It is a further object to provide a process for obtaining both a high free fatty acid and a high percentage of combined SO₃ in a sulphonated oil.

10 It is a further object of this invention to provide a process which can be carried out with greater expedition than the prior processes.

15 It is a still further object to shorten the time of sulphonation required in order to produce a high free fatty acid sulphonated oil of any given SO₃ content.

20 The above and other objects are achieved by this invention in a process which involves first sulphonating the oil by means of sulphuric acid or other suitable sulphonating agent; then dropping the sulphonated oil into a body of wash water, preferably containing at least enough alkali to neutralize the excess sulphonating agent; thereafter, if necessary, adding further

25 alkali to saponify the oil and produce an amount of soaps of the sulphonated fatty acids equivalent to the free fatty acid content desired in the final product; and finally adding sufficient mineral acid to the mass to decompose the soaps and produce the desired free fatty acid content.

30 The process of this invention is applicable to the various fatty ester bodies usually subjected to sulphonation processes such as the unsaturated and/or hydroxylated oils, fats and waxes.

35 Examples of suitable unsaturated oils include, inter alia, olive oil, teased oil, peanut oil, rice bran oil, menhaden oil, cod oil and the like. Suitable hydroxylated bodies include, among others, castor oil or oils which have been wet-blown to develop hydroxyl groups therein, such as wet-blown coconut oil. An example of an unsaturated wax suitable for use in this invention is sperm oil.

40 The sulphonation step may be carried out in any usual and suitable manner. Commonly, this will involve treating the oil with sulfuric acid at moderately low temperatures. However, if desired, other known sulphonation procedures and reagents, such as treatment with oleum, chlorsulphonic acid and the like, may be employed.

45 In the above process the body of water into which the oil from the sulphonation step is dropped preferably contains sufficient alkali to both neutralize the unsupent sulphonating agent

50

and to saponify the oil to produce an amount of fatty soaps equivalent to the amount of fatty acids desired in the final product; but the water may initially contain no alkali at all, or only a portion of the required amount, the necessary additional alkali being added subsequently. Likewise, the alkali may be added to the sulphonated mass before it is dropped into the body of water. In any event the total amount of alkali required may be readily calculated from the analysis of the oil just before it is dropped into the bath. Thus if the mass contains 20% excess acidity, calculated as sulphuric acid, due both to the unspent sulphuric acid and the acid sulphate radicles combined with the oil:

$$20\% \times \left(\frac{\text{NaOH}}{\frac{1}{2}\text{H}_2\text{SO}_4} \right) = 20\% \times \frac{40}{90} = 16\% \text{ NaOH}$$

must be added to just neutralize the unspent sulphonating agent. If it is desired to develop 25% free fatty acids, assuming a molecular weight for the triglycerides of 900:

$$25\% \times \left(\frac{\text{NaOH}}{\frac{1}{2} \text{glyceride}} \right) = 25\% \times \frac{40}{300} = 3\% \text{ NaOH}$$

must be added over and above that required for the neutralization of the unspent sulphonating agent. NaOH was cited above as being a suitable alkaline agent for neutralizing and saponifying the oil; however, any other suitable alkali such as KOH may be used.

It will be seen that in the process of the present invention the oil is never in contact for any extended time with acid aqueous solutions; and as a result, no splitting off of the sulphate groups in the oil will occur as it will in the conventional process. This has two advantages: first, that a sulphonated oil of higher SO₃ content may be obtained, and second, that sulphonation need not be prolonged in order to provide an excess of combined SO₃ to be split off during the conventional acid washing process.

Oils sulphonated in accordance with the procedure above set forth are distinguished from other oils heretofore made in that they possess a high content of both combined SO₃ and free fatty acids. Further, they are distinguished from earlier oils in that they are relatively more fluid at room temperature, which is believed to be due to the fact that in the acid panning processes of the prior art, the sulphate groups are split off from the fatty radicals, leaving hydroxyl groups in their place, which hydroxyl groups tend to the formation of solid products rather than liquid products. It will be noted that this last advantage is of lesser importance in the case of oils which were already hydroxylated before the sulphonation step, inasmuch as no additional hydroxy groups are introduced by the usual process. However, the advantage of securing both high free fatty and high SO₃ contents remains.

Following are examples illustrative of the process according to this invention and also, for comparison, of processes according to the prior art. All parts given are by weight.

Example I

100 parts of sperm oil were chilled to 15° C. and 35 parts of concentrated sulphuric acid were added thereto with stirring and with cooling to keep the temperature below 20° C. The stirring was continued for two hours, after which the resulting sulphonation mass was divided into two parts, one part being reserved for treatment in accordance with Example II below.

To 100 parts of the sulphonated mass produced as just described were added 92 parts of 24% aqueous caustic soda and the mass left to stand until a test for free alkali was negative. Thereafter sufficient sulphuric acid was added to the mass to reduce the total alkali to .2% and the entire mass was dropped into 200 parts of water, agitated therewith and "panned", i. e. allowed to settle overnight at 50° C. A sulphonated oil layer collected on the top and the salt water on the bottom was drawn off. Sufficient caustic soda (2% based on the weight of the oil) was added to clarify the oil. The resultant oil contained 25% moisture, had a free fatty acid content of 30% (including the fatty residues combined with the alkali as soap) and a combined SO₃ of 10%, and was a clear, reddish amber liquid oil.

Example II

To be distinguished from the present invention

100 parts of the reserved portion of the sulphonated mass prepared as above described in Example I were poured into 200 parts of water and sufficient soda added thereto to reduce the acidity to .5% (calculated as H₂SO₄ and based on the weight of the entire mass). The mass was kept in agitation until the free fatty acid content stopped increasing. Thereafter the mass was panned overnight at 50° C. and a layer of sulphonated oil separated out on top of the mass. The salt water layer was drawn off and sufficient caustic soda (2%) based on the weight of the oil was added to the oil to clarify the same. The resultant product contained 25% moisture, had a free fatty acid content of 20% (including the fatty residues combined with the alkali as soap) and a combined SO₃ content of 8%, and changed to a tan-colored solid upon cooling.

Example III

100 parts of peanut oil were chilled to 15° C. and 24 parts of concentrated sulphuric acid were added thereto with stirring and with chilling to keep the temperature below 20° C. The stirring was continued for 2 hours, after which the resulting sulphonated mass was divided into two parts, one part being reserved for treatment in accordance with Example IV below.

To 100 parts of the sulphonated mass produced as just described were added 60 parts of aqueous 24% caustic soda and the mass left to stand until a test for free alkali was negative. Thereafter sufficient sulphuric acid was added to the mass to reduce the total alkali to .2% and the entire mass was dropped into 200 parts of water, agitated therewith and panned at 50° C. overnight. The sulphonated oil layer collected on the top and the salt water layer on the bottom was drawn off. Sufficient alkali (2% based on the weight of the oil) was added to clarify the oil. The resultant oil contained 30% moisture, had a free fatty acid content of 58% (including the fatty residues combined with the alkali as soap) and a combined SO₃ of 10% and was a liquid oil which clouded slightly on cooling to room temperature.

Example IV

To be distinguished from the present invention

100 parts of the reserved portion of the sulphonated mass prepared as above described in Example III were poured into 200 parts of water and sufficient soda added thereto to reduce the acidity to .5% (calculated as H₂SO₄ and based on the weight of the entire mass). The mass was kept in agitation until the free fatty acid con-

tent no longer increased. Thereafter the mass was panned overnight at 50° C. and a layer of sulphonated oil separated out on top of the mass. The salt water was drawn off and sufficient alkali (2%) based on the weight of the oil was added to the oil to clarify the same. The resultant product contained 25% moisture, had a free fatty acid content of 25% (including the fatty residues combined with the alkali as soap) and a combined SO₃ content of 8% and was converted to a tan colored solid upon cooling.

Example V

100 parts of castor oil were chilled to 15° C. and 24 parts of concentrated sulphuric acid were added thereto with stirring and with chilling to keep the temperature below 20° C. The stirring was continued for 5 hours, after which the resulting sulphonated mass was divided into two parts, one part being reserved for treatment in accordance with Example VI below.

To 100 parts of the sulphonated mass produced as just described were added 51 parts of aqueous 24% caustic soda and the mass left to stand until a test for free alkali was negative. Thereafter sufficient sulphuric acid was added to the mass to reduce the total alkali to .2% and the entire mass was dropped into 200 parts of water, agitated therewith and panned at 50° C. overnight. A sulphonated oil layer collected on the top and the salt water layer on the bottom was drawn off. Sufficient alkali (2% based on the weight of the oil) was added to clarify the oil. The resultant oil contained 25% moisture, had a free fatty acid content of 42% and a combined SO₃ of 5% and was a clear, light-amber liquid oil.

Example VI

To be distinguished from the present invention

100 parts of the reserved portion of the sulphonated mass prepared as described above in Example I were poured into 200 parts of water and sufficient soda added thereto to reduce the acidity to .5% (calculated as H₂SO₄ and based on the weight of the entire mass). The mass was kept in agitation until the free fatty acid content no longer increased. Thereafter the mass was panned overnight at 50° C. and a layer of sulphonated oil separated out on top of the mass. The salt water was drawn off and sufficient alkali (6%) based on the weight of the oil was added to the oil to clarify the same. The resultant product contained 22% moisture, had a free fatty acid content of 42% and a combined SO₃ content of 2% and was a dark-colored, clear and fluid oil.

From the above examples it will be seen that in every case where the procedure of the present invention was followed with a given oil, the SO₃ content was not diminished from that obtained just at the finish of the sulphonation process, while in the case of the same oils processed according to prior procedures, the SO₃ content was diminished to a large extent. As above pointed out in the general discussion of this invention, this degradation is undesirable in that it is necessary to carry out a more drastic sulphonation in order to secure a product with any given SO₃ content. Further, the products according to the present invention, not having been subjected to splitting off of the combined SO₃, are not hydroxylated and are accordingly more fluid and clear than similar products heretofore manufactured. While the expressions "sulphonation" and "sulphonated" have been used in this application in accordance with their prior usage in

the art as commercially practiced, the process of the invention technically involves sulphation, i. e. formation of a sulphuric acid ester with the fatty molecules rather than the sulphonate derivatives.

Having described my invention what I claim as new and desire to secure by Letters Patent is:

1. Process of making a sulphonated material of high SO₃ having a substantial free fatty acid content from an ester type fatty body susceptible of sulphonation selected from the group consisting of oils, fats and waxes, which comprises subjecting such a body to a sulphonating agent to cause the same to combine with the desired amount of SO₃; saponifying the body to a sufficient degree to produce therein an amount of fatty soaps equivalent to the amount of free fatty acids it is desired to develop in the final body; and splitting said soaps to form the corresponding free acids in the sulphonated mass.
2. Process of making a sulphonated material of high SO₃ having a substantial free fatty acid content from an unsaturated fatty oil, which comprises subjecting said oil to a sulphonating agent to cause the oil to combine with the desired amount of SO₃; saponifying the oil to a sufficient degree to produce therein an amount of fatty soaps equivalent to the amount of free fatty acids it is desired to develop in the oil; and splitting said soaps to form the corresponding free acids in the sulphonated oil.
3. Process of making a sulphonated material of high SO₃ having a substantial free fatty acid content from a fatty oil containing at least one hydroxyl group, which comprises subjecting said body to a sulphonating agent to cause the oil to combine with the desired amount of SO₃; saponifying the oil a sufficient degree to produce therein an amount of fatty soaps equivalent to the amount of free fatty acids it is desired to develop in the oil; and splitting said soaps to form the corresponding free acids in the sulphonated mass.
4. Process of making a sulphonated material of high SO₃ having a substantial free fatty acid content from castor oil, which comprises subjecting said castor oil to a sulphonating agent to cause the oil to combine with the desired amount of SO₃; saponifying the oil a sufficient degree to produce therein an amount of fatty soaps equivalent to the amount of free fatty acids it is desired to develop in the oil; and splitting said soaps to form the corresponding free acids in the sulphonated oil.
5. Process of making a sulphonated material of high SO₃ having a substantial free fatty acid content from sperm oil, which comprises subjecting said oil to a sulphonating agent to cause the oil to combine with the desired amount of SO₃; saponifying the oil to a sufficient degree to produce therein an amount of fatty soaps equivalent to the amount of free fatty acids it is desired to develop in the oil; and splitting said soaps to form the corresponding free acids in the sulphonated oil.
6. Process of making a sulphonated material of high SO₃ having a substantial free fatty acid content from peanut oil, which comprises subjecting said oil to a sulphonating agent to cause the oil to combine with the desired amount of SO₃; saponifying the oil to a sufficient degree to produce therein an amount of fatty soaps equivalent to the amount of free fatty acids it is desired to develop in the oil; and splitting said soaps to form the corresponding free acids in the sulphonated oil.

7. Process of making a sulphonated material of high SO₃ having a substantial free fatty acid content from an ester type fatty body susceptible of sulphonation selected from the group consisting of oils, fats and waxes, which comprises treating such a body with sulphuric acid to cause the same to combine with the desired amount of SO₃; saponifying the body to a sufficient degree to produce therein an amount of fatty soaps equivalent to the amount of free fatty acids it is desired to develop in the final body; and splitting said soaps to form the corresponding free acids in the sulphonated mass.

8. Process of making a sulphonated material of high SO₃ having a substantial free fatty acid content from an ester type fatty body susceptible of sulphonation selected from the group consisting of oils, fats and waxes, which comprises subjecting such a body to a sulphonating agent to cause the same to combine with the desired amount of SO₃; saponifying the body to a sufficient degree to produce therein an amount of fatty soaps equivalent to the amount of free fatty acids it is desired to develop in the final body; splitting said soaps to form the corresponding free acids in the sulphonated mass; and panning said body in mildly alkaline solution to reduce the moisture content thereof.

9. Process of making a sulphonated material of high SO₃ having a substantial free fatty acid content from an unsaturated fatty oil, which comprises subjecting said oil to a sulphonating agent to cause the oil to combine with the desired amount of SO₃; saponifying the oil to a sufficient degree to produce therein an amount

of fatty soaps equivalent to the amount of free fatty acids it is desired to develop in the oil; splitting said soaps to form the corresponding free acids in the sulphonated oil; and panning said body in mildly alkaline solution to reduce the moisture content thereof.

10. Process of making a sulphonated material of high SO₃ having a substantial free fatty acid content from a fatty oil containing at least one hydroxyl group, which comprises subjecting said body to a sulphonating agent to cause the oil to combine with the desired amount of SO₃; saponifying the oil to a sufficient degree to produce therein an amount of fatty soaps equivalent to the amount of free fatty acids it is desired to develop in the oil; splitting said soaps to form the corresponding free acids in the sulphonated mass; and panning said oil in mildly alkaline solution to reduce the moisture content thereof.

11. Process of making a sulphonated material of high SO₃ having a substantial free fatty acid content from an ester-type fatty body susceptible of sulphonation selected from the group consisting of oils, fats and waxes, which comprises subjecting such a body to a sulphonating agent to cause the same to combine with the desired amount of SO₃; saponifying the body by treating it with a sufficient quantity of caustic alkali to produce therein an amount of fatty soaps equivalent to the amount of free fatty acids it is desired to develop in the final body; and splitting said soaps to form the corresponding free acids in the sulphonated mass.

CHARLES H. LIGHTHYPE.

CERTIFICATE OF CORRECTION.

Patent No. 2,344,154.

March 14, 1944.

CHARLES H. LIGHTHYPE.

It is hereby certified that error appears in the printed specification of the above numbered patent requiring correction as follows: Page 3, second column, line 36, claim 3, and page 4, second column, line 11, claim 10, for "body" read --oil--; and that the said Letters Patent should be read with this correction therein that the same may conform to the record of the case in the Patent Office.

Signed and sealed this 16th day of May, A. D. 1944.

Leslie Frazer

Acting Commissioner of Patents.
